CLAIM

The ornamental design for a catch basin, as shown and described.

DESCRIPTION

FIG. 1 is a top perspective view of a catch basin, showing my new design;

FIG. 2 is a bottom perspective view thereof;

FIG. 3 is a front elevational view thereof, the rear elevational view is identical;

FIG. 4 is a left side view thereof, the right side view is identical;

FIG. 5 is a top plan view thereof; and,

FIG. 6 is a bottom plan view thereof.

The broken lines in the figures are for the purposes of illustrating portions of the catch basin, which form no part of the claimed design.

1 Claim, 5 Drawing Sheets
